EX

OR 0 6,275

UNITED STATES PATENT OFFICE.

GEORGE F. MEACHAM, OF NEWTON, ASSIGNOR TO JAMES W. TUFTS, OF MEDFORD, MASSACHUSETTS.

DESIGN FOR CASING OF SODA-WATER APPARATUS.

Specification forming part of Design No. 6,275, dated November 26, 1872.

To all whom it may concern:

Be it known that I, GEORGE F. MEACHAM, of Newton, in the county of Middlesex and State of Massachusetts, have invented and produced a new and original Design for the Casing of a Soda-Water Apparatus, of which the following is a full, clear, and exact description, reference being had to the accompanying photograph making part of this specification.

In the photograph, A represents the casing of a soda-water apparatus, the lower portion of which, from *a* to *b*, is square in cross-section. Each of the four sides of the upper portion of the casing is inclined inward from *b* to *c*, and each of the four corners *d* is chamfered

or cut away on a curved line, thus forming a dome with an octagonal top, which is surmounted by a flat octagonal cap, *e*, the design thus produced being unique and ornamental.

What I claim as my invention, and desire to secure by Letters Patent, is—

The design for the casing of a soda-water apparatus, herein shown and described.

Witness my hand this 2d day of November, A. D. 1872.

GEO. F. MEACHAM.

Witnesses:

P. E. TESCHEMACHEE,
G. A. MEACHAM.
